THOMAS ALLATT, OF NEW YORK, N. Y., ASSIGNOR TO INTERNATIONAL CORK COMPANY,
OF BROOKLYN, NEW YORK, A CORPORATION OF NEW YORK.

DISK-SORTING MACHINE.

1,337,031.

Specification of Letters Patent. Patented Apr. 13, 1920.

Application filed March 29, 1919. Serial No. 286,073.

To all whom it may concern:

Be it known that I, THOMAS ALLATT, a subject of the King of Great Britain, and a resident of New York, in the county of 5 Richmond and State of New York, have invented certain new and useful Improvements in Disk-Sorting Machines, of which the following is a specification.

The present invention relates to sorting 10 machines for disks, such as for instance disks of cork or the like, which are used in the manufacture of crown-corks.

Before these disks are placed into the metallic caps of the crown-corks, they must 15 be carefully examined in order to remove from the mass such as are defective or imperfect. In examining these disks, heretofore the attendant had to pick up the same one after the other. Sometimes the disks 20 were placed onto a belt conveyer, the attendant being able to examine one of the faces of the disks, the same or another attendant picking the same up and inverting them in order to inspect the other faces thereof.

25 One of the objects of the invention is to provide a sorting device, which automatically turns over the disks traveling on a belt conveyer, one attendant examining the same in front of the turning means, and 30 another attendant in rear of said turning means, so that both faces of the disks may be inspected and the defective or objectionable ones removed without turning the same over.

35 With these and other objects in view, which will more fully appear as the nature of the invention is better understood, the same consists in the combination, arrangement and construction of parts hereinafter 40 described, pointed out in the appended claims and illustrated in the accompanying drawings, it being understood that many changes may be made in the size and proportion of the several parts and details of 45 construction within the scope of the appended claims without departing from the spirit or sacrificing any of the advantages of the invention.

One of the many possible embodiments of 50 the invention is illustrated in the accompanying drawings, in which:—

Figure 1 is a plan view of a disk sorting machine, constructed in accordance with the present invention; Fig. 2 is a section taken 55 on line 2—2 of Fig. 1; Fig. 3 is a section

taken on line 3—3 of Fig. 2, on a larger scale; Fig. 4 is a side elevation of the turning means; and Fig. 5 is a section taken on line 5—5 of Fig. 3, also on a larger scale.

In the drawings, the numeral 10 indicates 60 a frame, mounted upon legs or standards 11. In this frame are rotatably journaled rollers 12, over which passes a belt conveyer 12', that receives the disks to be sorted. The means for feeding these disks onto the 65 conveyer has not been shown, nor has the means been disclosed which serves to distribute or spread the disks throughout the width of the conveyer, as the same do not form part of the present invention. The 70 acting portion of the conveyer, that is to say that part thereof which transports the disks, travels in the direction of the arrow shown in Fig. 1 of the drawings and is divided into two sections, one of the same, denoted by the numeral 13, being arranged in a substantially horizontal plane that is located higher than the plane in which the section 14 of the conveyer moves, or in other 75 words a step is formed in the conveyer. 80

The disk turning or reversing means is disposed adjacent the step mentioned, and includes two frame sections 15, which are mounted upon the sides of the conveyer on the main frame 10, and form bearings for 85 a plurality of rollers presently to be described. One of these rollers, denoted by the numeral 16, is provided throughout its length with a resilient covering 17, made, for instance, by winding upon the said 90 roller a rubber tube. This roller extends transversely of the conveyer, its journals 18 being rotatably arranged in arms 19 that are fixed to a shaft 20, the latter being rotatably mounted in the frames 15 and provided with a lever 21, that is adapted to engage, for a purpose hereinafter to be described, a hook 22 upon a bracket 23, the latter being fixed to a tie-rod 24, connecting the frame sections 15. The journals 18 extend into slots 25 in the frames 15, to guide the movement of the roller 16, when the same is lifted so as to bring the lever 21 into engagement with the hook 22. The ends of the roller 16 are provided with flanges 26, 105 which are in frictional contact with the section 13 of the belt conveyer, whereby the said roller is caused to rotate in the direction of the arrow shown adjacent it in Fig. 5 of the drawings. The distance between the 110

Figure 1 is a plan view of a disk sorting machine, constructed in accordance with the present invention; Fig. 2 is a section taken on line 2—2 of Fig. 1; Fig. 3 is a section

upper surface of the section 13 of the conveyer and the resilient covering 17 of the roller 16 is less than the thickness of a single disk on the conveyer.

5 The roller 16 is held in engagement with the conveyer by springs 27, that are in engagement with the arms 19 and the frame 10.

With the roller 16 coöperates a, preferably, longitudinally ribbed roller 28, disposed in front of the roller 16 and journaled in the frames 15. This roller is of a smaller diameter than the roller 16 and is rotated, in a direction opposite to the direction of rotation of the roller 16, by means herein-10 after described, its surface speed being higher than that of the roller 16, say for instance three times the speed of the larger roller. The smaller roller is located at a distance from the roller 16 that is less than the 15 thickness of a disk. Above the roller 28 is rotatably journaled in the frame 15 a roller 29, having substantially the same diameter as the roller 28. The distance between these 20 two smaller rollers is smaller than the diameter of a disk, and the distance between the rollers 29 and 16 is considerably larger than the thickness of a disk. The roller 29 is disposed somewhat in front of the roller 28. The rollers 28 and 29 are rotated in the same 25 direction, for instance, by a chain 30 which runs over sprocket wheels 31 and 32, connected to the rollers 28 and 29, respectively. To the roller 28 is furthermore attached a 30 pulley 33, that receives motion from any suitable source of power by the intermediary of a belt 34. The rollers 28 and 29 rotate at the same speed, the sprocket wheels 31 and 32 being of the same size and containing the same number of teeth.

35 40 In front of the frames 15 is disposed an inclined plate member 35, that is attached to the said frames and leads down to the section 14 of the conveyer.

The operation of this device is as follows:—The normal positions of the elements 45 of the device are shown in detail in Fig. 5 of the drawings, in which the roller 16 is in its lower position and is driven by the belt 12', its surface speed corresponding to that 50 of the said belt.

The disks are spread, before they reach the roller 16, by suitable means and distributed so as to travel but one deep. As the disks pass under the roller 16, the 55 resilient covering of the latter is somewhat compressed at the point of contact and the disks advanced until they are brought between the roller 16 and the roller 28 co-operating therewith. These rollers rotate in 60 opposite directions and lift the disks bodily from the section 13 of the conveyer, the disks so lifted standing on the ribbed roller 28, when issuing from the two co-operating rollers, and the roller 29 preventing the same 65 from tilting forward. As the disks now

stand on the roller 28 and the latter rotates in the direction of the arrow shown in Fig. 5 of the drawings, the lowermost points of the disks (which are now in contact with the roller 28) move with the said roller and are 70 caused to reach first the inclined plate 35, on which they slide down onto the section 14 of the conveyer. In this manner the disks are turned over. To properly understand the 75 turning over operation, let us follow the course of one disk in Fig. 5 of the drawings. It appears from this figure that the exposed face 36 of a disk 37 faces the roller 16 not only when on the section 13 of the conveyer but also when standing on the roller 28. 80 When in this position, the opposite face 38 of the disk faces the roller 29, and as now the roller 28 advances the disk the latter will slide down on its face 36 on the inclined plate 35 and travel on the same face on the 85 section 14 of the conveyer.

From the foregoing it appears that the attendant, examining the disks while on the section 13 of the conveyer, is able to inspect 90 one of the faces of the disks and the attendant, examining the disks on the section 14 of the conveyer, the other faces thereof.

If, during the operation of the machine, foreign matter collects between the rollers 16 and 28, it becomes necessary to lift the 95 roller 16 to remove such matter, this may be accomplished by shifting the lever 21 and bringing the same into engagement with the hook 22 on the bracket 23. When these elements are disengaged, the springs 27 return the roller 16 to its normal, operative position. These springs serve mainly to hold the roller 16 in contact with the belt 100 conveyer section 13, but allow the said roller to rise, for instance, if two disks, one on top 105 of another, come within the reach thereof.

What I claim is:—

1. A machine for sorting disks, comprising a conveyer on which the disks travel on one of their flat faces, and means disposed above said conveyer for bodily lifting the disks from said conveyer and turning the same over.

2. A machine for sorting disks, comprising a conveyer of the endless belt type having its acting portion divided into two sections, one of said sections being located in a plane lower than the other one, means for bodily lifting the disks from the upper section of said conveyer and turning the same over, and an inclined plate leading from said turning means to the lower section of said conveyer, on which the disks slide onto the said lower section.

3. A machine for sorting disks, comprising a conveyer on which the disks travel on one of their flat faces, and two oppositely rotating rollers receiving the disks from and lifting the same above said conveyer so as to stand edgewise on one of said rollers, said 125 130

last-mentioned roller rotating in a direction to turn the disks over so as to rest on the flat faces opposite to those on which they previously traveled on said conveyer.

- 5 4. A machine for sorting disks, comprising a conveyer of the endless belt type having its acting portion divided into two sections, one of said sections being located in a plane lower than the other one, two oppositely rotating rollers receiving the disks from and lifting the same above the upper section of said conveyer so as to stand edgewise on one of said rollers, an inclined plate leading from said rollers to the lower section of said conveyer, the roller on which the disks are caused to stand edgewise rotating in a direction to turn the disks over so as to be brought onto said inclined plate on the flat faces opposite to those on which they travel on the upper section of said conveyer, and means coöperating with said lifting means for preventing the disks from tilting so as to be brought to rest on the faces on which they traveled before the lifting operation.
- 10 1) 5. A machine for sorting disks, comprising a conveyer on which the disks travel on one of their flat faces, means for bodily lifting the disks from said conveyer and turning the same over, and means coöperating with said lifting means for preventing the disks from tilting so as to be brought to rest on the faces on which they traveled before the lifting operation.
- 15 20 25 6. A machine for sorting disks, comprising a conveyer of the endless belt type having its acting portion divided into two sections, one of said sections being located in a plane lower than the other one, means for bodily lifting the disks from the upper section of said conveyer and turning the same over, an inclined plate leading from said turning means to the lower section of said conveyer on which the disks slide onto the said lower section, and means coöperating with said lifting means for preventing the disks from tilting so as to be brought onto said inclined plate on the faces on which they traveled before the lifting operation.

- 30 35 40 45 50 55 60 65 70 75 80 85 90 95 100 105 110 115 120 125 130
7. A machine for sorting disks, comprising a conveyer on which the disks travel on one of their flat faces, two oppositely rotating rollers receiving the disks from and lifting the same above said conveyer so as to stand edgewise on one of said rollers, said last-mentioned roller rotating in a direction to turn the disks over so as to rest on the flat faces opposite to those on which they traveled previously on said conveyer, and means coöperating with said lifting means for preventing the disks from tilting so as to be brought to rest on the faces on which they traveled before the lifting operation.
8. A machine for sorting disks, comprising a conveyer of the endless belt type having its acting portion divided into two sections, one of said sections being located in a plane lower than the other one, two oppo-

sitely rotating rollers receiving the disks from and lifting the same above the upper section of said conveyer so as to stand edgewise on one of said rollers, an inclined plate leading from said rollers to the lower section of said conveyer, the roller on which the disks are caused to stand edgewise rotating in a direction to turn the disks over so as to be brought onto said inclined plate on the flat faces opposite to those on which they travel on the upper section of said conveyer, and means coöperating with said lifting means for preventing the disks from tilting so as to be brought to rest on the faces on which they traveled before the lifting operation.

9. A machine for sorting disks, comprising a conveyer on which the disks travel on one of their flat faces, means for bodily lifting the disks from said conveyer and turning the same over, and rotary means coöperating with said lifting means for preventing the disks from tilting so as to be brought to rest on the faces on which they traveled before the lifting operation.

10. A machine for sorting disks, comprising a conveyer of the endless belt type having its acting portion divided into two sections, one of said sections being located in a plane lower than the other one, means for bodily lifting the disks from the upper section of said conveyer and turning the same over, an inclined plate leading from said turning means to the lower section of said conveyer on which the disks slide onto the said lower section, and rotary means coöperating with said lifting means for preventing the disks from tilting so as to be brought to rest on the faces on which they traveled before the lifting operation.

11. A machine for sorting disks, comprising a conveyer on which the disks travel on one of their flat faces, two oppositely rotating rollers receiving the disks from and lifting the same above said conveyer so as to stand edgewise on one of said rollers, said last-mentioned roller rotating in a direction to turn the disks over so as to rest on the flat faces opposite to those on which the previously traveled on said conveyer, and rotary means coöperating with said lifting means for preventing the disks from tilting so as to be brought to rest on the faces on which they traveled before the lifting operation.

12. A machine for sorting disks, comprising a conveyer of the endless belt type having its acting portion divided into two sections, one of said sections being located in a plane lower than the other one, two oppositely rotating rollers receiving the disks from and lifting the same above the upper section of said conveyer so as to stand edgewise on one of said rollers, an inclined plate leading from said rollers to

the lower section of said conveyer, the roller on which the disks are caused to stand edge-wise rotating in a direction to turn the disks over so as to be brought onto said inclined 5 plate on the flat faces opposite to those on which they traveled on the upper section of said conveyer, and rotary means coöperating with said lifting means for preventing the disks from tilting so as to be brought 10 to rest on the faces on which they traveled before the lifting operation.

13. A machine for sorting disks, comprising a conveyer on which the disks travel on one of their flat faces, two oppositely rotating rollers receiving the disks from and lifting the same above said conveyer so as to stand edgewise on one of said rollers, said last mentioned roller being disposed in front of and being of a smaller diameter 15 than the other one of said rollers, said smaller roller rotating in a direction to turn the disks over so as to rest on the flat faces opposite to those on which they previously traveled on said conveyer, and means 20 disposed above said smaller roller and in front of the larger roller for preventing the disks from tilting so as to be brought to rest on the faces on which they traveled before the lifting operation, said last-men- 25 tioned means being disposed from said smaller roller at a distance that is smaller 30

than the diameter of a disk and from said larger roller at a distance that is larger than the thickness of a disk.

14. A machine for sorting disks, comprising 35 a conveyer on which the disks travel on one of their flat faces, two oppositely rotating rollers receiving the disks from and lifting the same above said conveyer so as to stand edgewise on one of said 40 rollers, said last mentioned roller being disposed in front of and being of a smaller diameter than the other one of said rollers, said smaller roller rotating in a direction to turn the disks over so as to rest on the 45 flat faces opposite to those on which they previously traveled on said conveyer, and rotary means disposed above said smaller roller and in front of the larger roller for preventing the disks from tilting so as to be brought to rest on the faces on which they traveled before the lifting operation, said last-mentioned means being disposed from said smaller roller at a distance that is smaller 50 than the diameter of a disk and from said larger roller at a distance that is larger than the thickness of a disk.

Signed at New York, in the county of New York, and State of New York, this 11th day of Feb., A. D., 1919.

THOMAS ALLATT.
